DESIGN FOR WALL-PAPER.

SPECIFICATION forming part of Design No. 24,837, dated November 5, 1895.

Application filed September 30, 1895. Serial No. 564,223. Term of patent 3½ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

The design consists of a series of ornaments of the Empire style formed of an open wreath of leaves connected with ribbons, with a torch-like ornament at the top and a crown ornament in the center or open space formed by said ribbons, as represented in the accompanying drawing. The border of the design is also formed of similar ornaments of the Empire style and composed of an open wreath of leaves connected to a small ornament by a

bow of ribbon, with a crown ornament in the center and flamboyant torch-like ornaments on each side of said ornaments and connected by flowing ribbons, as shown in the drawing. Small fleur-de-lis ornaments are placed between the open-wreath ornaments and the torch-like ornaments, as shown.

What I claim is—

1. The design for wall paper herein shown and described.
2. In the design for wall paper, the border herein shown and described.

Witness my hand this 27th day of September, 1895.

CHARLES BOOZ.
